UNITED STATES PATENT OFFICE.

JEFFERSON S. PALMER, OF CLARK, SOUTH DAKOTA.

ADJUSTABLE SPARK-PLUG.

956,778.

Specification of Letters Patent. Patented May 3, 1910.

Application filed January 16, 1908. Serial No. 411,182.

To all whom it may concern:

Be it known that I, JEFFERSON S. PALMER, a citizen of the United States, residing at Clark, in the county of Clark and State of South Dakota, have invented certain new and useful Improvements in Adjustable Spark-Plugs; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in adjustable spark plugs, the object in view being to generally improve upon and render more efficient devices of this nature.

The invention consists in various details of construction, combinations and arrangements of parts which will be hereinafter fully described and then specifically defined in the appended claim.

My invention is illustrated in the accompanying drawings, in which:—

Figure 1 is a perspective view of the plug, showing the adjustable wire terminal attached thereto. Fig. 2 is a longitudinal section centrally through the plug. Fig. 3 is a detailed view of the adjustable terminal, and Fig. 4 is a detailed view of the adjustable jump spark screw.

Reference now being had to the details of the drawings by letter, A designates a plug casing having threaded circumference designed to engage the threaded aperture in the cylinder of an engine, and B is a lock nut having a threaded circumference designed to engage the threads on the inner wall of the casing.

C designates a porcelain insulator which is centrally apertured to receive the firing pin D. Said pin has a threaded end D', upon which is mounted a nut E. Mounted about said insulator is a packing ring G, made preferably of copper, and against which said lock nut B is adapted to bear, thereby preventing any leakage by the lock nut. Underneath the ring G is a packing G', preferably of asbestos to insure an air tight joint. A loop F is connected to the inner end of the casing at points diametrically opposite and said loop carries a jump spark screw H mounted in a threaded aperture in said loop. Said screw has a notch

in its inner end forming two points H'. By the provision of said loop mounted as shown, two currents of electricity are designed to flow to the jump spark screw, one from either side of the plug, both currents joining at the screw H and causing the positive current flowing through the pin D to jump to the two points of the screw H, thereby completing the circuit.

An adjustable wire terminal, designated by letter N, is provided having a slot N' therein adapted to receive the threaded portion of said firing pin and held in an adjusted position thereon by the nut upon the threaded end of the firing pin. Said terminal has a laterally projecting lug N² carrying a screw O upon which a threaded nut R is mounted, designed to coöperate with a nut S to securely hold a terminal wire. By this adjustable arrangement, it will be noted that, by sliding the terminal back and forth, the wire may be tightened and loosened as may be desired and also allowed to revolve about the firing pin.

By the construction of a sparking plug as shown and described, a simple and efficient device is afforded which will work under all conditions in a gas engine and affording two currents flowing through the plug, thereby doubling the efficiency of the plug, all leakage about the porcelain being prevented and the latter so constructed as to be adjustable in order to suit various gas mixtures and also adjustable for different voltage. By screwing in the jump spark screw and lessening the gap between the same and the firing pin, the plug will work on exceedingly weak batteries with satisfactory results and, by increasing the spark gap, the plug may be adjusted to a very strong voltage and give perfect results under various conditions. Owing to the enlarged air chamber in the bottom of the plug, the suction from the exhaust will clean out the air chamber at each explosion and a plug will be soot-proof. Owing to the adjustability of the terminal, the wires may be adjusted in any positions and may be readily removed by simply loosening the lock nut.

What I claim is:—

A hollow sparking plug comprising a shell with an enlarged chambered portion therein terminating in an inclined shoulder, the interior of said shell being contracted beyond the shoulder the one end of the shell having

a semi-cylindrical bridge loop, a screw fitted in an aperture therein and having terminal points, an insulating plug provided with an enlarged chambered portion adjacent to its inner end terminating in a shoulder and provided with a beading upon its circumference a short distance from its inner end, said beading adapted to rest upon the inclined shoulder in the shell with the portion 5 of the plug beyond said beading extending into the contracted portion of the opening beyond said chambered part, a headed screw passing through a longitudinal aperture in said plug and having its head seated upon 10 said shoulder at the inner end of said cham- 15

bered portion formed in the inner end of the plug, a contracted pin extension upon the head of said screw and forming a terminal, a cap fitted over the outer end of the plug and through which said screw passes, a nut 20 upon the threaded portion of the screw, and a gland about said plug and engaging said shell, as shown and described.

In testimony whereof I hereunto affix my signature in the presence of two witnesses. 25

JEFFERSON S. PALMER.
